FIG. 3.

UNITED STATES PATENT OFFICE.

SAMUEL SPIGELMAN, OF MALDEN, MASSACHUSETTS.

SNOW-REMOVING APPARATUS.

1,147,984.

Specification of Letters Patent. Patented July 27, 1915.

Application filed November 12, 1913. Serial No. 800,576.

To all whom it may concern:

Be it known that I, SAMUEL SPIGELMAN, a citizen of the United States, residing at Malden, in the county of Essex and State of Massachusetts, have invented certain new and useful Improvements in Snow-Removing Apparatus, of which the following is a full, clear, and exact specification.

This invention relates to snow plows, and has for its object the provision of apparatus for removing the snow from the streets and carrying it away in addition to clearing a track or passageway.

Heretofore the function of a snow plow has been to displace the snow from one part of a street or sidewalk to another part adjacent thereto, the snow thus piled up along the edge of the cleared part being subsequently removed by wagons into which it is loaded by hand shovels.

My present invention contemplates the clearing of an entire street or sidewalk, if desired, and the removal or transportation of the snow at the same time. Thus, my improved apparatus is adapted and designed to carry off the snow cleared from the street or sidewalk in addition to clearing a passageway, and to perform both operations successively and continuously, whereby a single trip of my apparatus down a street or sidewalk will result in the complete removal of substantially all the snow which has fallen at the time said apparatus passes.

The apparatus is equally well adapted for use on a line of railway for clearing between and adjacent the tracks.

Another object of the invention is to remove the ice with the snow, and to this end means are provided for releasing or breaking away the ice from the pavement in advance of the plow.

A further object is to provide means for moving the snow taken up by the apparatus, from one conveyance to another and for discharging the snow from the conveyance into which it is finally stored, when a suitable dumping place is reached.

The invention will be first hereinafter described in connection with the accompanying drawings, which constitute a part of this specification, and then more specifically defined in the claims at the end of the description.

In the accompanying drawings, wherein similar reference characters are used throughout the several views to designate corre-

sponding parts Figure 1 is a side elevation of snow removing apparatus constructed in accordance with my invention, the lateral guides being removed to disclose the opening in the side of the car into which the snow is guided and from which it is raised by the rotary scoop. Fig. 2 is a sectional plan showing the ice picks arranged in front of the plow, the lateral guide plates or strips, and the rotary scoop. Fig. 3 is a central vertical longitudinal section through the snow removing apparatus as illustrated in Fig. 1. Fig. 4 is an enlarged detailed cross section of the rotary scoop in connection with the cam for operating the devices which positively clear or discharge the snow from the scoops. Fig. 5 is a detailed side view of the cam just mentioned.

The mechanism or apparatus for taking up the snow is mounted on the snow plow, or rather on the car or vehicle having the plow on its front end. This car or vehicle is illustrated in Figs. 1, 2 and 3, and comprises a body 12 generally rectangular in form with sides which reach down near to the surface of the street or roadway, as at 13, Fig. 1. The front end of this vehicle or car is equipped with a snow plow 14 of suitable form for throwing the snow to either side 85 of the car.

Projecting through slots or openings 15 in the front of the car are a plurality of ice picks 16 which are mounted on a crank shaft 17, Figs. 2 and 3, by which they are adapted to be reciprocated. In front and a little below the crank shaft there is a cam shaft 18 having cams 19 adapted to engage the respective picks and raise their outer ends as they are being moved forward by the crank shaft. The crank shaft and the cam shaft are both driven by a suitable motor 20, Fig. 3, by means of the sprocket chain 21 and gear 22, the latter being interposed between the two shafts so that they are rotated in the same direction. It will be understood that alternate cranks extend in opposite directions, so that alternate picks are drawn inward or rearward while the others are being thrust or moved outward or forward, and that the cams are so arranged with respect to the cranks that each pick will be raised as it is thrust outward or forward and allowed to fall at the end of such outward or forward movement. Springs 23 may be used to insure the proper dropping of said picks when the cams pass from below them or for

increasing the force of the blow delivered by the picks in falling. By means of these picks it will be seen that the ice which usually forms under the snow will be loosened or chopped from the pavement in advance of the plow, so that said ice will be thrown to either side with the snow as the plow advances.

Openings 24 are provided in each side of the car, preferably about centrally thereof and opposite each other. To the rear edge of each of said openings there is hinged a guide plate or strip 25, extending outward and forward at a desired angle to a point in advance of the plow. These guide strips are adjustably connected to the sides of the car by chains 26, by means of which the angle thereof with respect to the car may be varied so as to cover the entire width of the street, if desired. As a further means of accomplishing this object, the strips may be each made in two or more sections adjustably connected together at 27, whereby they may be lengthened when necessary to cover wide streets. As will be obvious the guide strips 25 direct the snow into the openings 24 in the sides of the car, that is to say the snow which has been thrown by the plow from in front of the car as well as the snow lying at either side of the said car.

The openings 24 lead to a chamber 28 in which the rotary scoop 22 is arranged. This chamber 28 has a curved cover 30 extending over the forward half thereof, while the rear half of the top of said chamber is left open. The rotary scoop has a plurality of blades 31 extending substantially radially but somewhat curved to better take up and hold the snow in operation. Said scoop fills the chamber, and the partial cover 30 is arranged just beyond the path of the ends or outer edges of the blades, so that there is no chance of the snow escaping or falling from said scoop as it is being raised. After the snow is raised by the rotary scoop, it is discharged through the open portion of the top of the chamber 28 onto a platform 32 in the rear part of the car.

In order to insure the discharge of the snow from the blades of the scoop, I provide clearers 33, one of which is hinged to the outer edge of each blade and in one position fits closely against the rear face of each blade. The clearers are yieldingly held in this position by springs 34 and remain so during the greater portion of the revolution of the scoop. Roller bearings 35, carried by the free edges of the clearers 33, are adapted to ride on fixed cams 36 for the purpose of moving said clearers outward as they successively come opposite the partial opening in the top of the chamber 28, see Figs. 3, 4 and 5. These cams 36 are of such shape as to not only throw the clearers outward to a position where they occupy substan-

tially one-quarter of the line of travel of the outer edges of the blades when said blades successively come to the margin of the opening in the top of the chamber, but also hold said clearers out in that position until their respective blades reach the level of the platform 32; when the cam permits the springs 34 to quickly draw them in again so as to leave their respective blades unobstructed when their turns come for taking up the snow. It will thus be seen that as each blade of the rotary scoop reaches a position opposite the opening in the top of the chamber 28, the snow which has been raised thereby is positively discharged on to the platform 32 by its clearer 33 working on the cam 36.

The rotary scoop may be driven by a train of gears 37 from a motor 38. Also driven from said train of gears are two crank shafts 39 and 40 arranged above the scoop. The crank shaft 39 is attached to the bracket 41 of the transverse plunger or pusher 42 which is adapted to slide upon the platform 32. The crank of the shaft 40 is arranged below the bracket 41 and is adapted to engage said bracket for raising the plunger 42 at proper intervals. As shown in Fig. 3, the shafts 39 and 40 are preferably geared to turn in the same direction and at the same speed. The cranks of said shafts preferably extend in substantially the same direction, so that they turn in unison. The gearing from the motor 38 to the shafts 39 and 40 and to the rotary scoop is so arranged and proportioned as to cause one reciprocation of the plunger 42 during each quarter revolution of the scoop, the forward movement of said plunger beginning when each blade of the scoop reaches the edge of the opening in the top of the chamber 28, as shown in Fig. 3. Of course, if the rotary scoop had a greater or less number of blades, the plunger would be made to reciprocate once during the travel of each blade across the opening in the top of the chamber in which said scoop is mounted, the size of said opening being varied to correspond to the distance between the outer edges of adjacent blades.

By reason of the arrangement of the crank shafts 39 and 40, above described, the plunger 42 will be moved forward along and in contact with the platform, but as it is drawn rearward again, the crank on the shaft 40 will raise said plunger, thereby carrying it over the snow which has accumulated on the forward end of the platform. The result is that after each reciprocation of the plunger the same is brought back to the position shown in Fig. 3 with some of the snow behind it to be pushed back on its next reciprocation. It will thus be seen that as my snow removing apparatus is moved forward in operation the snow from the

whole width of the street or roadway is directed into the chamber 28 from whence it is raised or conveyed by the rotary scoop to the platform 32, and the snow thus deposited on the platform is pushed back along the same to the rear end of the car which may be closed, if desired, by a door 43.

Having thus fully described my invention, what I claim as new and desire to secure by Letters Patent of the United States, is:—

1. In an apparatus of the character described, the combination with a vehicle having a centrally-situated snow plow at its front end adapted to force the snow in the path of the vehicle laterally as the latter moves, and a snow-collecting chamber in the rear of the plow, said chamber having 15 side inlet openings, wings extending outwardly and forwardly from the sides of the vehicle for directing the snow into said openings, and means for taking up the snow from said chamber.

2. In an apparatus of the character described, the combination with a vehicle having a centrally-situated snow plow at its front end adapted to force the snow in the path of the vehicle laterally, as the latter moves and a snow-collecting chamber in the rear of said plow provided with side inlet openings, wings secured to the sides of the vehicle in the rear of said openings and extending outwardly and forwardly from said 25 vehicle to direct the snow through said openings, and means for taking up the snow accumulated in said chamber.

3. In an apparatus of the character described, a vehicle having a snow plow and a 30 snow-collecting chamber in the rear thereof and in line therewith, snow-elevating means in said chamber, and laterally and forwardly-extending wings attached to the vehicle in rear of the elevating means for 35 guiding the snow at the sides of the plow to said chamber and elevating means.

4. In an apparatus of the character described, the combination with a snow plow, of picks extending forwardly over the plow 40 and having ice-cutting portions situated in advance of the plow, and pick-actuating means situated in the rear of the plow, said means comprising devices to raise the picks, and means to cause said picks to strike 45 hammer-like blows.

5. In an apparatus of the character described, the combination with a snow plow, of picks extending forwardly over the plow 50 and having ice-cutting portions situated in advance of the plow and pick-actuating means situated in the rear of the plow, said means comprising devices to raise the picks, and springs connected to the picks to cause 55 them to strike hammer-like blows.

6. In apparatus of the character described,

the combination with a snow plow, of a plurality of ice picks extending in front of the plow, means situated in the rear of the plow for reciprocating said picks and raising them, springs for giving the picks their ice-cutting movement, and means in the rear of the plow for taking up the snow that is forced laterally by the plow.

7. In apparatus of the character described, the combination with a snow plow, of a plurality of ice picks pivotally mounted in the rear of the plow and extending in front thereof, means for reciprocating said picks and raising them as they are moved forward, and means for causing each pick to 70 deliver a hammer-like blow at the end of its forward movement.

8. In apparatus of the character described, the combination with a snow plow, of a plurality of ice picks extending in front of the plow, and means situated in the rear of the plow for reciprocating said picks and raising springs for giving the picks their ice-cutting movement forward and means in the rear of the plow for taking up the snow that 80 is forced laterally by the plow.

9. In apparatus of the character described, the combination with a snow plow, of a plurality of ice picks pivotally mounted in the rear of the plow and extending in front thereof, means for reciprocating said picks and raising them as they are moved forward, and means for causing each pick to 85 deliver a hammer-like blow at the end of its forward movement.

10. In apparatus of the character described, the combination with a vehicle having a crank shaft thereon provided with a plurality of cranks, the adjacent ones of which extend in opposite directions, of ice 95 picks connected to said cranks, and a cam shaft arranged in front of the crank shaft and below the picks, said cam shaft having cams to engage the respective picks and raise them as they are moved forward.

11. In a device of the class described, the combination with a vehicle having a snow-collecting chamber provided with inlet openings at the sides of the vehicle, of laterally-extending members for guiding the snow toward the vehicle and into said openings as the vehicle moves along, said members being made in sections which are adjustably connected together to allow for longitudinal adjustment, and means for elevating the snow 110 collected in said chamber.

12. In an apparatus of the character described, the combination with a vehicle having a snow-collecting chamber provided with inlet openings at the sides of the vehicle, of means to guide the snow at the sides of the vehicle into said openings as the vehicle moves forward, means to elevate the snow from said chamber into the body 115 of the vehicle, and means for pushing the 120

4
snow toward the rear of the body after it has been elevated.

13. The combination with a vehicle having a snow collecting chamber, of a rotary 5 scoop fitted in said chamber for elevating the snow therefrom into the body of the vehicle, said scoop having a plurality of radial arms, and the chamber having a partial cover extending over the front part thereof 10 and curved to conform to the path of the outer edges of said arms and means for positively discharging the snow from between the radial arms at the rear of said cover.

14. The combination with a vehicle having 15 a snow collecting chamber, of a rotary scoop fitted in said chamber for elevating the snow therefrom into the body of the vehicle, said scoop having radial arms, devices for discharging the snow from said arms, 20 said devices being yieldingly held in a collapsed position, and means for moving said devices outward at the proper times.

15. The combination with a vehicle having 25 a snow collecting chamber, of a rotary scoop fitted in said chamber for elevating the snow therefrom into the body of the vehicle, said scoop having radial arms, discharging devices hinged at the outer edges of said arms and adapted to lie against the 30 backs of said arms or to be turned outward for discharging the snow from the following arms, means for yieldingly holding the discharging devices against the backs of the arms, and means for moving said devices 35 outward at proper times.

16. The combination with a vehicle having 40 a snow collecting chamber, of a rotary scoop fitted in said chamber for elevating the snow therefrom into the body of the vehicle, said scoop having curved radial arms, curved discharging devices hinged at the outer edges of said arms and adapted to lie against the backs of said arms or to be turned outward to a position substantially 45 coincident with the path of the outer edges of the arms for discharging the snow from

the following arms, means for yieldingly holding the discharging devices against the backs of the arms, and means for moving said devices outward at the proper times. 50

17. The combination with a vehicle having 55 a snow collecting chamber, of a rotary scoop fitted in said chamber for elevating the snow therefrom into the body of the vehicle, said scoop having radial arms, discharging devices hinged at the outer edges of said arms and adapted to lie against the backs of said arms or to be turned outward for discharging the snow from the following arms, means for yieldingly holding the 60 discharging devices against the backs of the arms, projections on the lateral edges of said devices, and a cam arranged in the path of said projections for moving the devices outward at the proper times. 65

18. The combination with a vehicle having 70 a snow collecting chamber, of means for elevating the snow from said chamber into the body of the vehicle, a reciprocating plunger for pushing the snow delivered into said vehicle body toward the rear end thereof, and means for raising said plunger as it is moved forward.

19. The combination with a vehicle having 75 a snow collecting chamber, of means for elevating the snow from said chamber into the body of the vehicle, a crank shaft arranged transversely of said vehicle, a plunger having a bracket pivotally connected to the crank of said shaft, whereby 80 said plunger may be reciprocated, and another crank shaft having its crank adapted to engage the bracket and raise the plunger as the same is moved forward.

In testimony whereof I have signed my 85 name to this specification in the presence of two attesting witnesses.

SAMUEL SPIGELMAN.
